US00D645372S

(12) **United States Design Patent**
Hall et al.

(10) **Patent No.:** US D645,372 S
(45) **Date of Patent:** ** Sep. 20, 2011

(54) **DETECTOR COWLING**

(75) Inventors: **David L. Hall**, Pontiac, MI (US);
Andrew D. Frost, Berkley, MI (US)

(73) Assignee: **Air Products and Controls Inc.**,
Pontiac, MI (US)

(**) Term: **14 Years**

(21) Appl. No.: **29/380,020**

(22) Filed: **Nov. 29, 2010**

(51) LOC (9) Cl. **10-05**

(52) U.S. Cl. **D10/106.2**

(58) **Field of Classification Search** D10/106.2,
D10/106.4; 340/542-545, 555, 558, 628,
340/630, 571-73, 577, 579

See application file for complete search history.

(57) **CLAIM**

The ornamental design for a detector cowling, as shown and
described.

DESCRIPTION

FIG. 1 is a perspective view of an inventive cowling;
FIG. 2 is a top view of the inventive detector cowling depicted
in FIG. 1;

FIG. 3 is a left side view of the inventive detector cowling depicted
in FIG. 1;

FIG. 4 is a back side view of the inventive cowling depicted in
FIG. 1;

FIG. 5 is a front side view of the inventive detector cowling
depicted in FIG. 1; and,

FIG. 6 is a bottom view of the inventive detector cowling
depicted in FIG. 1.
